PERFORATED-EMBOSSED LEATHER OR SIMILAR FABRIC

Abraham R. Kaplan, Great Neck, N. Y.

Application September 21, 1953, Serial No. 26,877

Term of patent 14 years

(Cl. D87—3)

To all whom it may concern:

Be it known that I, Abraham R. Kaplan, a citizen of the United States of America and a resident of Great Neck, in the county of Nassau and State of New York, have invented a new, original, and ornamental Design for a Perforated-Embossed Leather or Similar Fabric, of which the following is a specification, reference being had to the accompanying drawing, forming a part hereof, wherein:

Fig. 1 is a plan view of a perforated-embossed leather or similar fabric, showing my new design; and

Fig. 2 is a section taken on line 2—2 of Fig. 1.

I claim:

The ornamental design for a perforated-embossed leather or similar fabric, substantially as shown.

ABRAHAM R. KAPLAN.
